DESIGN FOR A DOLL

Agnes S. Hammerly, Duluth, Minn.

Application May 24, 1947, Serial No. 139,251

Term of patent 7 years

(Cl. D34—4)

To all whom it may concern:

Be it known that I, Agnes S. Hammerly, a citizen of the United States, residing at Duluth, in the county of St. Louis and State of Minnesota, have invented a new, original, and ornamental Design for a Doll, of which the following is a specification, reference being had to the accompanying drawing, forming part thereof.

In the drawing

Fig. 1 is a front elevational view of a doll, showing my new design;

Fig. 2 is a side elevational view of the doll shown in Fig. 1.

I claim:

The ornamental design for a doll, as shown.

AGNES S. HAMMERLY.
